(57) **CLAIM**

The ornamental design for a paragraph indicator bookmark, as shown and described.

DESCRIPTION

FIG. 1 is a back view of a paragraph indicator bookmark showing my new design.

FIG. 2 is a right edge view of the paragraph indicator bookmark.

FIG. 3 is a left edge view of the paragraph indicator bookmark.

FIG. 4 is a top view of the paragraph indicator bookmark.

FIG. 5 is a bottom view of the paragraph indicator bookmark; and,

FIG. 6 is a perspective front view of the paragraph indicator bookmark. The hatched lines are for illustrative purposes only and do not form any part of the design.
